United States Patent Office.

WILLIAM W. WEBSTER, OF CHELSEA, MASSACHUSETTS.

Letters Patent No. 110,704, dated January 3, 1871.

IMPROVEMENT IN CONSTRUCTING MOLDINGS OF PAPER.

The Schedule referred to in these Letters Patent and making part of the same.

Be it known that I, WILLIAM W. WEBSTER, of Chelsea, in the county of Suffolk and State of Massachusetts, papier-maché manufacturer, have invented certain new and useful Improvements in the manufacture of Paper-Moldings, especially adapted for the cornices of rooms in buildings, but applicable to other situations; and I do hereby declare that the following is a full, clear, and exact specification thereof, reference being had to the accompanying drawings and to the letters of reference marked thereon.

Similar letters represent similar parts in the several views.

A practicable cornice for rooms, lighter and less expensive, and free from the objections of wood or stucco cornices, and one that can be put up dry, after the building is finished, has long been a great desideratum; this I deem myself to have accomplished by my present invention.

Papier-maché work is of two kinds, viz.: Molded work, of which cornices, brackets, and ornaments of various kinds have been heretofore composed, and layer-work, as it is called, which has been used exclusively for tables, boxes, and other flat extended work.

My present improvement consists in making cornices which are not of too-complicated outline, of paste-board or papier-maché, by the layer process.

The annexed drawings represent a room-cornice, of simple form, constructed in my improved manner.

Figure 1 is a cross-section.

Figure 2, a front view, on an angle of forty-five degrees.

a a represent portions of the wall and ceiling of the room.

b represents the cavetto or principal molding of the cornice, which I make by pasting layers of paper on a mold of proper form, until I attain the requisite thickness for stability.

Then to keep the molding in perfect shape, and prevent all twisting and warping, I coat the back of the molding at *c* with thick enamel composition.

I then put the same up, either in sections or of the entire lateral dimensions of the room, and complete the outline of the cornice, to meet the requirements of taste, by adding fillet-moldings, represented by the letters *d* and *e*, either of wood, "molded papier-maché," or of any other material, which fillets may serve not only for ornament, but to support and confine the cavetto or principal molding.

When the cavetto or layer-work is put up in sections, I usually conceal the joinings by an additional front exterior layer of paper, *f*, of finer texture and color, which I put on after the sections are secured in place; and I frequently enrich the cornice by the addition of ornaments of putty-composition or molded papier-maché, as represented by the letters *g g*.

Having thus described the nature, use, and application of my improvement,

I claim—

A paper cornice, made and applied in the manner and for the purpose described.

WILLIAM W. WEBSTER.
